UNITED STATES PATENT OFFICE

158,899

ENVELOPE MOISTENER OR THE LIKE

Harry O. Sandberg, Boston, Mass.

Application August 20, 1949, Serial No. 4,633

Term of patent 14 years

(Cl. D74—10)

To all whom it may concern:

Be it known that I, Harry O. Sandberg, a citizen of the United States, residing at Boston, county of Suffolk, State of Massachusetts, have invented a new, original, and ornamental Design for an Envelope Moistener, or the like, of which the following is a specification, reference being had to the accompanying drawings, forming a part thereof.

Fig. 1 is a perspective view of an envelope moistener or the like showing my new design, and Fig. 2 is a bottom plan view thereof, the handle being broken away for convenience of illustration.

I claim:

The ornamental design for an envelope moistener or the like, substantially as shown.

HARRY O. SANDBERG.
